UNITED STATES PATENT OFFICE.

SAMUEL S. WILLIAMS, OF CHICAGO, ILLINOIS, ASSIGNOR OF ONE-HALF OF HIS RIGHT TO ROBERT BRAUDHUBER, OF SAME PLACE.

IMPROVEMENT IN AUTOMATIC FEEDING DEVICES FOR HORSES.

Specification forming part of Letters Patent No. 221,887, dated November 18, 1879; application filed February 7, 1879.

To all whom it may concern:

Be it known that I, SAMUEL S. WILLIAMS, of Chicago, in the county of Cook and State of Illinois, have invented certain new and useful Improvements in Stables and Stable-Fixtures, of which the following, in connection with the accompanying drawings, is a specification.

Figure 1, Sheet 1, is a front view of the fixtures to which my invention relates; Fig. 2, Sheet 1, a section in the plane of the line xx ; Fig. 3, Sheet 2, a front view of one of the graduated disks; and Fig. 4, Sheet 2, a side view of the parts shown in Fig. 3.

Like letters of reference indicate like parts.

A represents a stable or stall for horses. B is the feed box or trough. C is a supplemental box or feed-holder arranged above or over the box B, and having an inclined front, as shown. D is a swinging valve or shelf, forming the bottom of the box C. The valve D is rigidly attached to a rocking lever, E, having suitable bearings, and projecting beyond the box C, by preference.

F is an arm or lever, pivoted or hinged at its rear end to the wall of the stable, and projecting therefrom to a sufficient extent to have much force as a lever when employed in the manner hereinafter described. G is a link or connecting-arm, pivoted or hinged to the rear end of the crank or arm of the lever E, and looped freely over the lever F. H is a rotary shaft, in the forward part of which is cut a spiral groove or worm, I. J is a link or loop connected to the forward end of the lever F, and looped over and resting freely upon the spiral or worm I. K is a stop passing freely through the loop of the link J.

The shaft H may be rotated automatically in any suitable way—for example, by means of clock-work, as indicated at a —the direction of the rotation being such as to slowly carry the upper end of the link J toward the forward or grooved end of the shaft. When the link J is supported by the shaft H, the valve or shelf D is thereby held in such a position as to close the bottom of the box C, and consequently grain or feed will then be retained in the said box, if there placed, for being fed to the horse, it being understood that this box will contain enough to furnish one feeding. When the

upper end of the link J reaches the forward end of the shaft H, this link slips off therefrom and falls upon the stop or support K. The valve D then has no support. Consequently the feed in the box C is dumped or falls into the box B, where the horse may have access to it.

My purpose in providing means for dumping the feed automatically into the feed-boxes may be explained as follows: Many horses are employed in work requiring them to be fed very early in the morning, and consequently the person having charge of them must be up much earlier in order to feed them. If the shaft H rotates once in one hour, the link J will be advanced in that time one thread of the spiral or worm I, and if there are ten circuits of the spiral, the link will drop from its support in ten hours from the time it is arranged to be caught by the rear end of the spiral. Therefore, if I wish to have my horse fed at 6 a. m., I place in the box C his feed for that morning, having hung the link J on the rear end of the spiral I at 8 p. m. of the evening before, (which, it may be supposed, is the time of feeding at evening,) and having wound up the clock mechanism, I may then feel assured that the horse will have access to his food at 6 a. m., and consequently I need not then go to the stable to feed him.

It may be perceived that by a very simple calculation the link J may be so arranged that the horse will be fed at a different hour. For example, if I wish the horse fed at 5 a. m., it is only necessary to arrange the link J one spiral forward of that in which it was before arranged. To arouse the horse and give notice of the proper working of the mechanism, a gong, L, may be employed, the hammer of which may be connected to any of the down-moving parts released when the link J is released—for example, by means of a cord, M, to the arm of the lever E. A disk, N, properly graduated, may also be employed in connection with an index-hand, O, on the shaft H, to denote how long the clock mechanism has run at the time the link J is to be set. The clock mechanism may also be utilized to indicate the hour of the day, as illustrated at b .

Having thus described my invention, what I claim as new, and desire to secure by Letters Patent, is—

1. The combination of the feed-holder C, the trap or valve D, the rock-lever E, the suspending-lever F, the connecting-links G and J, and the spirally-grooved rotary shaft H, substantially as and for the purposes specified.

2. The combination of the feed-holder C, the trap or valve D, the spirally-grooved rotary shaft H, the rock-lever E, and means for suspending the said lever on the worm of the said shaft, substantially as and for the purposes specified.

3. The combination of a clock or chronometer, the rotary worm-shaft H, and the tilting

valve D, supported or suspended on the said shaft, in connection with a feed-holder and feed-box, substantially as and for the purposes specified.

4. The combination of the gong L with the tilting valve or bottom D of the feed-holder C and mechanism for controlling the said valve automatically, substantially as and for the purposes specified.

SAMUEL S. WILLIAMS.
